Inventor:
Edward F. Carry

By Gilliland Mann Atteys.

UNITED STATES PATENT OFFICE.

EDWARD F. CARRY, OF CHICAGO, ILLINOIS.

DRAFT GEAR.

Application filed November 8, 1923. Serial No. 673,429.

To all whom it may concern:

Be it known that I, EDWARD F. CARRY, a citizen of the United States, and resident of Chicago, county of Cook, and State of Illinois, have invented certain new and useful Improvements in Draft Gears, of which the following is a specification, and which are illustrated in the accompanying drawings, forming a part thereof.

This invention relates to draft gears and has for its principal object to oppose the permissible movement of the draw bar with a hydraulic brake that will offer resistance suitable to the energy of the shock and will insure smooth operation in both directions.

Further objects will appear and be more clearly understood as the disclosure proceeds and the description is read in connection with the accompanying drawings illustrating a selected and preferred embodiment of the invention, and in which—

Fig. 1 is a longitudinal sectional view showing the parts in neutral position;

Fig. 2 is an end view looking at Fig. 1 from the right;

Figs. 3 and 4 are sectional views taken on the lines 3—3 and 4—4 of Fig. 1;

Fig. 5 is a sectional view taken on the line 5—5 of Fig. 2, and

Fig. 6 is a view similar to Fig. 1, illustrating the parts in the positions they assume as the draft gear approaches the end of its movement on buff.

Particular description of the embodiment here shown.

A draw bar is conventionally shown at 10 connected with a draw bar extension 11 by a familiar pivot joint 12. Center sills 40 are shown at 13 and the car floor is indicated at 14.

The hydraulic brake includes a main cylinder 15 and a smaller auxiliary cylinder 16 cast in one piece which is provided with flanges 17 and 18 that are secured to the center sills by rivets or bolts 19 and 20. The ends of the cylinders are closed by heads 21 and 22 which have annular flanges 23 and 24 telescoping with the respective cylinders and circumferential flanges 25 and 26 secured to the cylinders by machine bolts or the like 27.

A piston 28 divides the main cylinder into two chambers 29 and 30. A piston rod 31, connected to piston 28, has a tapered end 32 seated in a complementary socket in a cross

head 33 and secured therein by a key 34. The cross head is carried by the end of the draw bar extension opposite to the pivot joint 12.

The cylinder heads 21 and 22 are provided with cylindrical barrels 35 and 36 which receive springs 37 and 38 extending between the remote ends of these barrels and the opposite sides of the piston 28. The piston rod 31 forms a guide for the spring 38 and the cylinder head 21 is equipped with a tubular guide 39 for the spring 37.

The piston rod 31 passes out of the barrel 36 through a stuffing box 40 having a movable gland 41 by means of which the box can be adjusted.

The upper portions of the flanges 23 are cut away and the cylinder walls are equipped with tapered ports 42 and 43 leading from the main cylinder to the auxiliary cylinder. The piston 28 carries a valve 44 for throttling these ports to decrease or increase their area according to the direction of movement of the piston. The valve 44 is equipped with soft metal liners 45 pressed against the valve seat 46 by springs 47.

The auxiliary cylinder is fitted with a floating piston 48 which divides it into two chambers 49 and 50. The cylinder heads 21 and 22 are provided with barrels 51 and 52 forming extensions of the auxiliary cylinder and receiving the auxiliary springs 53 and 54 which extend between the remote ends of these barrels and the opposite sides of the auxiliary piston 48. Guides 55 and 56 formed on the piston and the cylinder heads respectively serve to keep the springs in position.

The upper portion of the auxiliary cylinder is equipped with filling plugs 57 made accessible through openings 58 in the car floor and the lower portion of the main cylinder is equipped with drain plugs 59 by which the system may be emptied.

The upper portions of the heads 21 and 22 are equipped with air chambers 60 and 61 which communicate with the interior of auxiliary cylinders adjacent to the bottom thereof through small passages 62 and 63, opening through the bottom of the hollow guides 56.

The auxiliary piston is formed with flanges 64 which serve as valves to throttle the ports 42 and 43, as the auxiliary piston moves towards the opposite ends of the auxiliary cylinder. The cylinder head 22 car-

ries brackets 65 and 66 equipped with guides 67 and 68 for the cross head 33.

Operation.

5 When a shock is received in the direction of the arrow 69 in Fig. 1, the piston 28 will move to the right with speed and power dependent upon the energy of the shock. This movement will be resisted, first by the 10 spring 37, and the liquid in the chamber 29, which latter escapes through the port 42 into the chamber 50, compressing the air in the chamber 60.

If the shock is light, no action of the other 15 parts is required to absorb and dissipate its energy, and sufficient liquid will pass by gravity through the port 43 into the chamber 30 to prevent rebound of the piston 28.

If the shock has sufficient energy to develop pressure in the chamber 50 necessary to overcome the spring 54 and the friction between the piston 48 and the walls of the auxiliary cylinder, that piston will begin to move, which will result in the displacement of liquid in the chamber 49 and cause it to be forced through the port 43 into the chamber 30 in proportion to the enlargement of that chamber due to the movement of the piston 28. The acceleration of the flow of liquid through the port 43 will increase the resistance to that flow which will react through the piston 48 and the liquid in the chamber 50 and increase the resistance of the liquid in the chamber 29, and thus increase the braking action on the piston 28. At the same time the valve 44 is throttling the port 42, which also increases the resistance to escape of liquid from the chamber 29, and therefore the braking action.

40 If the shock has sufficient energy to continue the movement of the pistons the valve 64 will throttle the port 43, again increasing the resistance to be overcome by the piston 48 which will react through the chambers 50 and 29 upon the piston 28.

Finally, if the energy of the shock is sufficient the valve 64 will close or nearly close the port 43, enormously increasing the resistance offered to the piston 48, and again reacting through the liquid in the chambers 50 and 29 upon the piston 28.

In this condition of the gear the piston 48 can get relief only through compression of the air in the chamber 61 and the piston 28 can get further relief only through compression of the air in the chamber 60, through a small portion of the port 42 left open. Thus the gear will offer extremely high resistance as it approaches closed position, but this approach will be cushioned by the pneumatic action of the air in the chambers 60 and 61.

The chamber 30 will be kept filled behind the piston 28 and as soon as the shock is 65 spent the compressed air in the chambers

60 and 61 the spring 54 and the spring 37 will start the parts back to their normal position. However, since the recovery of normal position is accompanied by less speed, the passage of the liquid through the ports 70 will be opposed by correspondingly less resistance.

Upon receipt of a shock in the direction opposite to the arrow 69 in Fig. 1, the operation of the gear is the same though the 75 movement of the parts is in the reverse direction.

General discussion.

The auxiliary cylinder acts as a reservoir 80 insuring that the main cylinder will always be filled, to the end that the piston 28 will meet with braking resistance whether it is moved by a shock or is recovering after a shock and the liquid automatically alters 85 that resistance to accord with the speed of the piston. By causing the liquid escaping from the main cylinder before the piston to force liquid through the port behind the piston it greatly increases the capacity of the 90 gear. In this connection the piston 48 serves as a pressure operated delay action valve to throttle the port behind the piston 28 or opposite to the direction in which it is moved and thus further increases the capacity 95 of the gear.

The use of the auxiliary cylinder permits the necessary storage capacity to be obtained within the limited available space 100 and allows the gear to be made as a single unit that can be readily attached to and removed from the car.

The air chamber directly subject to the pressure of the liquid escaping from the main cylinder serves to cushion the initial movement of the gear and renders its action smooth and easy; the other air chamber cushions the succeeding stage of the operation when the auxiliary piston begins to move; and the two chambers jointly cushion the final movement of the gear to prevent abrupt closure.

The adjacent ends of the ports 42 and 43 being larger than the remote ends, the initial flow of liquid will be comparatively free and afford maximum relief when the energy of the shock is at maximum; then, as the energy of the shock is absorbed, the valve 44 will rapidly close the port before the piston, or toward which it is moving; then, as the energy is further absorbed, the valve 64 will more rapidly close the port behind the piston, or away from which it is moving; and, finally, when the shock is spent, the liquid before the piston can escape only through a much reduced port against the cushioning of the air chambers. Furthermore, due to the fact that the resistance offered by a given port is dependent upon the speed with which the liquid is forced to pass through it, 130

the gear automatically adjusts itself to shocks of different energy.

It is contemplated that the auxiliary cylinder will be kept filled and the air in the 5 chambers 60 and 61 will take care of expansion and contraction in addition to their cushioning functions. Since they communicate with the oil chambers adjacent to the bottom and through small ports, the entry 10 and egress of oil thereto will be throttled and there will be neither foaming of the oil nor escape of air into the oil chamber. Simply filling the cylinders will cause the necessary air to be trapped in the air chambers. 15

The springs take care of the ordinary fluctuations in acceleration and retardation of the train in motion and the hydraulic brake will be brought into action chiefly by sudden 20 shocks in buffering, starting and stopping. When the train is in motion the pull or push on the draw bar will cause the piston 28 to be slightly displaced and thus increase the capacity of the gear in case of sudden application 25 of the brakes. The advantage of this will be apparent when it is remembered that the brakes take effect first at the locomotive and then progressively along the cars to the rear of the train and always the braking 30 action of the locomotive is superior to that of any car.

The auxiliary springs 53 and 54 acting through the piston 48 serve in conjunction with the air chambers to cushion the action 35 of the gear and to assist the main springs 37 and 38 in restoring the gear to normal condition after absorbing the shock.

I am aware that some of the features of this draft gear may be used to advantage 40 without other features here shown associated therewith and that many of the features may be modified to adapt the gear to particular uses, and therefore do not wish to be limited by the language and drawings used to make 45 this disclosure, but intend to secure protection commensurate with the invention in every particular.

I claim as my invention:

1. In a device of the class described, the 50 combination of a primary hydraulic cylinder, a piston therein, springs tending to maintain the piston in a neutral position, an auxiliary hydraulic cylinder communicating with the primary hydraulic cylinder 55 through ports arranged on opposite sides of the piston, a floating piston in the auxiliary cylinder, springs tending to maintain the floating piston in a neutral position, and a valve moving with the first piston to throttle 60 said ports.

2. In a device of the class described, the 65 combination of a primary hydraulic cylinder, a piston therein, springs tending to maintain the piston in a neutral position, an auxiliary hydraulic cylinder, a floating

piston therein, tapered ports connecting the cylinders on opposite sides of the piston and a valve moving with the first piston to close said ports.

3. In a device of the class described, the 70 combination of a primary hydraulic cylinder, a piston therein, springs tending to maintain the piston in a neutral position, an auxiliary hydraulic cylinder, a floating piston therein, tapered ports connecting the cylinders on opposite sides of the pistons, a valve moving with the first piston to close said ports, and an air cushion communicating with the auxiliary cylinder on each side of the floating piston. 80

4. In a device of the class described, the combination of a primary hydraulic cylinder, a piston therein dividing the cylinder into two chambers, an auxiliary cylinder, 85 ports connecting the auxiliary cylinder with each of the chambers of the primary cylinder and a pressure operated valve for throttling the port behind the piston.

5. In a device of the class described, the combination of a primary hydraulic cylinder, a piston therein dividing the cylinder into two chambers, an auxiliary cylinder, ports connecting the auxiliary cylinder with each of the chambers of the primary cylinder, a valve operated by movement of the 90 piston for throttling the port in front of the piston and a pressure operated valve for throttling the port behind the piston. 95

6. In a device of the class described, the combination of a primary cylinder, a piston dividing the cylinder into two chambers, an auxiliary smaller cylinder, a floating piston dividing the auxiliary cylinder into two chambers, ports connecting the corresponding chambers on opposite sides of the pistons and valves operated by the pistons for 100 throttling the ports. 105

7. In a device of the class described, the combination of a cylinder, a piston dividing the cylinder into two chambers, an auxiliary chamber communicating with the cylinder through ports on each side of the piston, a valve moving with the piston for closing one of said ports, and a delay action valve 110 for closing the other of said ports. 115

8. In a device of the class described, the combination of a cylinder, a piston dividing the cylinder into two chambers, an auxiliary chamber communicating with the cylinder through ports on each side of the piston, a valve moving with the piston for closing one of said ports, and a second valve moving more swiftly than the first to close the other port. 120

9. In a draft gear, the combination of a 125 cylinder, a piston in the cylinder, an auxiliary chamber communicating with the main cylinder through ports on opposite sides of the piston, air chambers communicating with the opposite ends of the auxiliary 130

chamber and a valve for closing the port behind the piston.

10. In a device of the class described, the combination of a main cylinder, a piston in the main cylinder, an auxiliary cylinder communicating with the main cylinder through ports on opposite sides of the piston, an auxiliary piston in the auxiliary cylinder, resilient means tending to retain the pistons in normal position, an air chamber communicating with the auxiliary cham-

ber and means for throttling the port behind the main piston.

11. In a draft gear, the combination of an hydraulic cylinder, a piston in the cylinder, a reservoir communicating with the cylinder, means for throttling the flow of liquid when the piston is moving and means for effecting a secondary throttling of the liquid as the movement continues.

EDWARD F. CARRY.
